CLAIM

The ornamental design for a combined warp thread carrier, thread and adhesive holding strip therefor, substantially as shown and described.

DESCRIPTION

FIG. 1 is a perspective view of a combined warp thread carrier, thread and adhesive holding strip therefor, showing my new design;
FIG. 2 is a front elevational view thereof;
FIG. 3 is a left end elevational view thereof;
FIG. 4 is a right end elevational view thereof; and
FIG. 5 is a rear elevational view thereof.
